UNITED STATES PATENT OFFICE.

GARDNER C. HAWKINS, OF BOSTON, MASSACHUSETTS, ASSIGNOR OF ONE-HALF TO WALLACE G. WEBBER, OF BEDFORD, MASSACHUSETTS.

CAR-SEAT.

SPECIFICATION forming part of Letters Patent No. 731,361, dated June 16, 1903.

Application filed May 20, 1902. Serial No. 108,168. (No model.)

To all whom it may concern:

Be it known that I, GARDNER C. HAWKINS, of Boston, in the county of Suffolk and State of Massachusetts, have invented certain new and useful Improvements in Car-Seats, of which the following is a specification.

This invention relates to seats for use in railway-cars of the type employing a swinging support and a pair of chairs mounted to rotate on said support, so as to face toward either end of the car, the support being adapted to project either crosswise of the car or lengthwise thereof, the seats then facing the aisle of the car. Seats of this nature have heretofore employed means for locking the chairs in fixed angular positions on the swinging support and independent means for locking the swinging support in fixed angular positions on its base.

The object of the present invention is to provide means whereby the swinging support may be automatically unlocked from its base by the rotation of the chairs on said support. I thus avoid two operations which have been heretofore required when it has been desired to swing the support from its position crosswise of the car to its position lengthwise thereof, or vice versa, and at the same time rotate the chairs—namely, the operation of unlocking the chairs on their support and the separate operation of unlocking the support from its base.

Of the accompanying drawings, Figure 1 represents a vertical section of a car-seat constructed in accordance with my invention. Fig. 2 represents a plan view, partly in section. Fig. 3 represents a section on the line 3-3 of Fig. 1. Fig. 4 represents a section on the line 4-4 of Fig. 1, showing the locking means for the swinging support in locked position. Fig. 5 represents a similar view showing the locking means in unlocked position.

The same reference characters indicate the same parts in all the figures.

Referring to the drawings, 10 represents a base adapted to be secured to the floor of the car, and 11 represents a support or arm mounted to swing pivotally on said base.

12 are chairs carried by the support 11 and having spindles 13 journaled in bear-

ings on the support, said spindles being provided with pinions 14, engaging toothed segments 15 on the ends of a pivoted horizontally-swinging arm or lever 16. By virtue of this connection between the chairs they are caused to rotate in unison, so that both chairs may be rotated by grasping either one of them and reversing it.

17 is a spring-pressed locking-bolt adapted to engage a series of notches 18, formed in the lever 16, whereby the said lever is locked so as to hold the chairs in different rotative positions on the support 11, but permitting said chairs to be automatically unlocked by the exertion of sufficient rotative force.

I do not herein claim the specific form of connection and locking means above described, as the same is made the subject of a separate application, Serial No. 91,972, filed by me.

For the purpose of locking the swinging arm 11 in different rotative positions on the base 10 I provide a vertically-sliding locking-bolt 19, carried in a socket in the hub of the arm 11 and having at its lower end a projecting lug 20, adapted to engage any one of a series of notches 22, formed in a locking-segment affixed to the base 10. An upwardly-pressing spring 24 normally elevates the bolt, so as to force its lug 20 into engagement with the notches 22. The bolt 19 carries a roller 25 at its upper end adapted to be engaged by a cam projection 26, formed on the lower side of the swinging lever 16. When the chairs 12 are in their locked positions, the roller 25 is off the cam 26, as shown in Fig. 4, and the bolt 19 is allowed to lock with the segment 23, and thus hold the swinging arm in a fixed angular position on the base 10; but when either of the chairs 12 is grasped and rotated on its own axis the swinging of the lever 16 causes the cam 26 to ride over the roller 25 and depress the bolt 19, thereby releasing it from locking engagement with the segment and permitting the arm 11 to be swung to a different angular position on the base 10.

It will be observed that the axis of rotation of the right-hand chair 12 in the drawings coincides with the axis of rotation of the arm 11, so that a swinging movement imparted to

the latter does not vary the distance of said chair from adjacent fixed objects, such as the side of the car. In other words, the right-hand chair has a movement of rotation, but no movement of translation. The base 10 can therefore be located with the vertical axis of the chair at a distance from the side of the car corresponding to the horizontal distance from said axis to the most protrusive part of the chair-back, thereby securing a maximum amount of aisle-space when the chair-arm 11 is thrown longitudinally of the car.

I do not wholly confine myself to the constructional embodiment of my invention herein set forth, as the automatic unlocking of the swinging support can be obtained by many methods differing in detail.

I claim—

- 20 1. In a car-seat, the combination of a swinging support, means to lock said support against swinging movement, a chair mounted to rotate on said support, and mechanism actuated by the rotation of said chair for automatically releasing said locking means.
- 25 2. In a car-seat, the combination of a swinging support, means to lock said support against swinging movement, two chairs mounted to rotate on said support, and mech-

anism actuated by the rotation of either of said chairs for automatically releasing said locking means.

3. In a car-seat, the combination of a swinging support, means to lock said support against swinging movement, two chairs mounted to rotate on said support, a connection between said chairs for causing them to rotate in unison, and means on said connection for automatically releasing said locking means when the chairs are rotated.

4. In a car-seat, the combination of a base provided with a locking member, a support mounted to swing on said base, a locking-bolt carried by said support and adapted to engage said locking member, means yieldingly pressing said bolt into engagement with said locking member, a chair mounted to rotate on said support, and a cam operated by the rotation of said chair and adapted to force said bolt out of locking engagement with said locking member.

In testimony whereof I have affixed my signature in presence of two witnesses.

GARDNER C. HAWKINS.
